CLAIM

The design for a golf ball retriever head, as shown and described.

DESCRIPTION

FIG. 1 is a perspective view of a golf ball retriever head showing my new design;

FIG. 2 is a perspective view similar to FIG. 1 with the wing portions in the retracted position; and,
FIG. 3 is a rear perspective view.

The broken line showing of the shaft in FIGS. 1-3 is for illustrative purposes only and forms no part of the claimed design.
